CLAIM

The ornamental design for a video images playback unit, as shown and described.

DESCRIPTION

FIG. 1 is a top, front and side perspective view of a video images playback unit, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2; and,

FIG. 8 is a front, top and side perspective view thereof showing a cover thereof raised.

The broken line showing of a tape and a remote control unit is for illustrative purposes only and forms no part of the claimed design.

FIG. 1

FIG. 2

FIG. 3

FIG. 4
